To all whom it may concern:

Be it known that I, Aaron Guzy, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a front view of the dress unit of the dress ensemble shown in Figure 1.

Figure 3 is an enlarged view of an embroid-

ered cut-out unit appearing on the bust portion of the dress member of the ensemble, shown in Figure 2.

Figure 4 is a rear view of the jacket unit of the dress ensemble.

The rear portion of the dress unit is conventional.

The characteristic feature of my design resides in the combination on the dress as shown of the embroidered cut-outs, as shown.

I claim:

The ornamental design for a dress ensemble, substantially as shown, and described.

AARON GUZY.
